FIG. 10.

FIG. 11.

FIG. 12.

UNITED STATES PATENT OFFICE

LUCIEN L. TORREY, OF LOS ANGELES, CALIFORNIA

REFRIGERATING PLANT

Application filed February 18, 1928. Serial No. 89,119.

This invention relates to improvements in refrigerating plants.

One of the features of this invention is to provide a self-contained refrigerator having 5 therein a mechanical refrigerating plant and operating by air-cooling; and in which the circulating fan is employed for ventilating an apartment.

Another feature is to provide an electrical 10 system for such air cooled plants, which may be controlled thermostatically in accordance with refrigerating requirements, or manually at the desire of the attendant where an apartment is to be ventilated when the refrigerating 15 thermostat control has stopped the power plant.

A further object is to provide ventilating ducts for such air-cooled apparatus whereby the air may be drawn from or delivered to the 20 exterior of the apartment as desired.

Another feature is to provide ventilating means whereby the obnoxious gases escaping in event of leakage may be discharged outside the apartment.

Another feature is the construction of a 25 rigidly and compactly assembled unit having the driving mechanism, air ventilating fan, and gas compressor mounted with the appropriate reducing gearing upon a base which 30 contains the cooling pipes and the storage reservoir for the liquid refrigerant.

Another feature is the arrangement of the 35 air ventilating fan, the cooling pipes, and the base in such manner that fresh and cool air is being drawn in at a point distant from the exit of the heated air.

Further features are the simple and rigid 40 assembly of the several parts of the unit with regard to each other, whereby space and weight are conserved; the employment of packings about the driving shaft so as to prevent escape of obnoxious gas, and the presence of an oiling system for this shaft which 45 prevents the escape of such gases during replenishment of oil.

With these and other objects in view, as 50 will appear in the course of the following specification and claims, the drawings illustrate one form of execution of this invention.

In the drawings:—

Figure 1 is a section through a refrigerator according to this invention, showing the various elements in place, and diagrammatically representing the several connections of the 55 various parts.

Fig. 1^a is a detail view showing the damper operating lever for controlling the flow of air.

Fig. 2 is a horizontal section substantially 60 on the line 2—2 of Fig. 1.

Fig. 3 is a diagram of the electrical connections in Figs. 1 and 2.

Fig. 4 is a section substantially on line 4—4 of Fig. 5 showing the air cooled refrigerating 65 unit according to this invention.

Fig. 5 is a section of the same substantially 70 on line 5—5 of Fig. 4.

Fig. 6 is an enlarged detail section on line 6—6 of Fig. 5.

Fig. 7 is a cross-section through the expansion tank of this invention.

Fig. 8 is a section substantially on line 8—8 of Fig. 7.

Fig. 9 is a horizontal section substantially 75 on the line 9—9 of Fig. 7.

Fig. 10 is a diagrammatic view in section through a room, showing the apparatus connected to the inlet and outlet pipes for the cooling air.

Fig. 11 is a detail view on much larger scale showing one of the damper devices for controlling the flow of cooling air through the various pipes.

Fig. 12 is a detail of a damper handle and 85 its sector plate.

The refrigerator as shown in Fig. 1 comprises the outer heat-insulating casing 100 having therein the horizontal bottom heat-insulating partition 101 and an intermediate 90 vertical partition 102 having the apertures 102^a and 102^b. The base of the refrigerator is closed on all sides by the casing 100^a and has a bottom 103 spaced from the floor upon which the refrigerator is placed. An intermediate partition 104 separates the bottom compartment into two separate chambers 105 and 106, which may be closed substantially 95 air-tight by a front door. On the rear of the refrigerator is mounted a vertical stack 107 100

which extends from the top of the refrigerator downward to a point opposite the bottom compartments 105 and 106. Branching from this vertical pipe 107 are the horizontal branch pipes 108 and 109 which have their respective orifices 110 and 111 opening into the respective bottom chambers 105 and 106. In alignment with the vertical pipe 107 is a vertically disposed pipe 112 which leads 5 downward to the base of the refrigerator. The pipes 107 and 112 are open to the apartment respectively at the top and the bottom end. A damper 113 is pivotally mounted on a shaft 114, and may occupy either of the 10 two end positions designated by the letters S and W in Fig. 1. The shaft 114 carries on the outside of the pipe system the crank arm 115 with the crank pin 116. An operating shaft 117 projects through the structure of 15 the refrigerator box from the front face thereof and carries at its rear end a crank arm 118 having a slot 119 therein to engage with the crank pin 116 (Fig. 1^a). On the front end of the shaft 117 may be disposed a 20 suitable handle and indicator for operation by the attendant. Accordingly as the shaft 117 is rotated clockwise, or counterclockwise as in Fig. 1, the damper 113 will be rocked respectively into the W or the S positions, 25 and thus place the pipes 107 and 112 in alternate communication with the pipes 109 and 108.

30 Mounted in the compartment 106 is a refrigerating unit of the type to be more fully described hereinafter, which as its base 10 is mounted upon the bottom 103 of the refrigerator, and has an electric motor 11 to drive the ventilating fan 12, which is disposed opposite an opening 120 in the partition 104, 35 so that during the operation of the motor 11, air is drawn by the fan from the chamber 105 and forced downward through the pipe 19 and the base 10 of the unit and delivered through the aperture 21 into the compartment 106.

40 It will be understood that when the damper 113 is in the position S, the air from the upper portion of the room will be withdrawn through the pipes 107 and 108 and through 45 the aperture 110 into the chamber 105, thence passing through the fan 12 and conduit 19, the base 10 and then through the aperture 21 into the chamber 106, from which it further passes through the aperture 111 by pipes 109 and 112 to be discharged from the bottom end 50 of the latter. It will be understood that extension pipes such as those shown in dotted lines at 121 and 122 may be attached respectively to the pipes 107 and 112 so that air 55 from near the ceiling of the room may be drawn into the pipe 107 and the air from pipe 112 may be discharged through the conduit 122 to the exterior of the building.

60 On the contrary, when the damper 113 is 65 in the position W, air is drawn, for example,

from the exterior of the building through the pipe 122, into the pipe 112 and thence passes by pipe 108 and aperture 110 into the chamber 105 from which, in the same manner as before, it is drawn by fan 12 and discharged intermediately into the chamber 106, from 70 which it flows through the aperture 111 and pipes 109 and 107 and is finally discharged near the ceiling of the room.

75 By means of this regulatable ventilating system, it is possible to withdraw the warm air from the room as desired and discharge it to the exterior or to supply fresh air from the exterior at a relatively low temperature and warm it by passage over the refrigerating unit and discharge it into the room. A further advantage to be obtained from this arrangement is that the bottom compartment of the refrigerator is constructed substantially airtight, and in the event of a break 80 or leakage of any part of the refrigerating unit and pipes associated therewith, any foul or offensive gases escaping are passed into the chamber 106: the attendant then can easily move the damper 113 into position S, 85 and thereafter all such gases are discharged through the pipe 112 to the exterior, and hence are prevented from injurious effects upon the health of persons within the apartment.

90 It is preferred to construct the base 10 and the motor 11 and compressor 13, 66, as well as the casing of the fan 12 and the intermediate partition 104 as a rigid assembly, so that it may be easily and quickly 95 withdrawn from the lower compartment after the door to the same has been removed and the connections to the several pipes 60 and 64 have been severed at appropriate unions provided for that purpose. To facilitate the separation of the unit, the electric motor is provided with the lead or power wires 125 which are connected to a detachable plug 126 mounted in the wall of the connecting box 127. This box in turn is 100 connected by a duplex cord 128 with a current tap 129. It will be understood that proper fuses may be mounted within this box as shown at 130 in Fig. 3. For the control of the electric motor, it is preferred to 105 provide a thermostatic element 131 located within the food compartment of the refrigerator and connected by the conductors 132 passed through suitable conduits to the box 127, as shown in Fig. 3. In order to obtain 110 a manual control of the motor independent of the thermostat arrangement, a manual switch 133 is mounted upon the face of the refrigerator and adapted to short-circuit the thermostat 131 when desired.

115 The refrigerating unit consists of a base 10 having mounted thereon the electric driving motor 11, a ventilating fan with the casing 12, and a crank case casting 13 of a compressor pump. Within the base 10 is a liquid 120

refrigerant tank 14 and a cooling coil 15. The base is closed substantially air-tight at its bottom by the plate 16 which is held in place by the screws 17. The fan casing 12 has the impeller element 18 driven from the electric motor 11, for delivering air under pressure through the conduit 19 and an aperture in the top of the base 10. The air flows through the base, over and around the coiled pipe 15 and over and under the baffle plates 20 arranged in the base, until it makes its exit through an aperture 21 on the far side of the base. It will be understood that the cold air passes over these pipes and cools their contents gradually and finally makes its escape at a distance from, and is discharged in a direction opposite to, the inlet to the ventilating fan 12.

It will be understood that air may be passed in either direction through the condenser in accordance with its construction and operation, so that the air is caused to travel through the base and thus cool the tubing. In this way fresh and cold air is being constantly passed through the base. It is preferred normally to pass the air from the fan to the coils.

The electric motor 11 is mounted on the offset integral portion 22 of the base 10, and has the coupling 23 upon its shaft, and thereby drives the shaft 24 and worm 25 of a transmission having the worm wheel 26. The worm wheel 26 is mounted within the casting 27 which is secured upon the crank case 13 of the compressor, and carries at its top a further casting 28 for the reception of the worm. At the compressor end of the worm shaft 24 is indicated a self-aligning thrust ball bearing 29, which may be adjusted by the threaded bushing 30. It will be noted that the motor end of the worm shaft 24 is supported directly upon the motor shaft by a flexible coupling, so that a free movement is afforded to the worm shaft and the motor and shaft may operate together at a high rate of speed without danger of bending the shafting.

Near the motor end of the worm shaft 24 is mounted a collar 24^a, which projects laterally of the shaft and into an annular groove 28^a provided in the bore of the casting 28 which accommodates the shaft; this groove in turn communicates by a pipe 28^b with the interior of the casting 27. It will be understood that as the motor drives the worm 25 and thereby the worm wheel 26, oil contained in the casing 27 will be carried around and onto the worm 28 and will flow along the shaft 28 thereof to lubricate the several parts. In order to prevent a throwing of oil to the exterior, or a wastage at the motor end of the shaft 24, this collar 24^a will divert the oil as splashed, or will permit it to drop or be flung into the groove 28^a, which collects

and delivers it through the passage 28^b back into the interior of the casting 27.

The worm wheel 26 is keyed upon the driving shaft 31, which is journaled at one end in the bearing bushing 32 in the end of the casting 27. This shaft 31 is carried in a bored hole in the casting boss 67 and successively passes through a packing 33, through an oil chamber 34, another packing 35, a bearing bushing 36, and into the crank case 13 of the compressor, in which it is provided with offset cranks or eccentrics for the connecting rods 37, 37 which actuate the pistons 38, 38. This shaft is also provided with the ball thrust bearings 39 to prevent endwise movement of the shaft, and with a bearing bushing 40 mounted in the wall of the crank case 13.

The lubrication of the two bearings of this shaft adjacent the crank case is assured by the wicks 41, 41 which dip downward into the body of oil contained in the bottom of the crank case 13. To assure a proper lubrication of the eccentrics or cranks 37, their surfaces are lubricated by similar wicks 42 carried at the lower part of their structure, likewise dipping into the oil during operation.

A tightening bushing 43 having the tightening screws 44^a is provided to compress the packings 33 and 34. In order to hold these packings spaced apart and under a constant pressure during operation of the device, a spring 44 is mounted within the oil bore 34 and pressing at each end against the plates or washers 46, which in turn press against the packings 33 and 35.

As shown in Fig. 6, the oil bore 34 is in communication by the cored passages 47 with an annular cored passage 48 which surrounds the entire shaft and constitutes an oil reservoir for maintaining an ample supply of oil above the level of the packings and spring. All these chambers are formed integrally in the casting boss 67. By the use of this double packing, gases are prevented from passing from the interior of the crank-case 13 through the packing 35 into the oil bore 34 and the oil reservoir 48 connected therewith. If, after wear on the shaft and bearings, such passage does occur, the further packing 33 prevents the gases from having access to the interior of the casting 27 in which the worm wheel 26 is located.

In order to supply oil to the oil reservoir 48, the oil cup 50 is provided with a hermetically closable screw top 51 and a valved outlet 52, and may be threaded into the connection 53 in the top of the oil reservoir 48. If it be desired to replenish oil or to deliver a further supply into the oil reservoir 48, the cover 51 may be removed, the oil cup 50 filled and the cover replaced. When the valve 52 is opened the oil will flow into the oil reservoir 48 irrespective of any pressure differences or the presence of any gases in the oil reservoir 133.

48. It will be noted that no offensive gases escape from the reservoir 48 during the filling operation.

It will be understood that the compressor 5 is provided with the usual inlet valves 55 in the heads of the pistons, and the outlet valves 56 in the compressor head block 57. The gases returning from the refrigerating system are delivered through the pipe 60 into 10 the crank case 13 of the compressor, and are sucked therefrom and compressed within the cylinders of the compressor and delivered through the compressor head block 57 to the discharge pipe 61, which has a closing valve 15 62. The discharge from the pipe 61 is into the cooling coil 15 in the base of the unit. The hot compressed gases from the compressor are cooled in this coil 15 until they condense, and are delivered through the terminal pipe 63 into the liquid refrigerant tank 14. The liquefied refrigerant may be drawn off through the discharge pipe 64 and the controlling valve 65 therefor to the usual expansion valve, after which they are employed 20 for cooling, and then return again in the expanded and warmed condition through the pipe 60 to renew the cycle.

The structure is assembled by bolting the 30 crank case 13 onto the assembled base 10 by the bolts 65, and then bolting the compressor cylinder casting 66 which has the offset boss 67 containing the packings 33, 35 formed integrally therewith upon this crank case casting 13. The shafts and pistons may then 35 be mounted, and the packings tightened down by the bushing 43. The worm wheel 26 is then placed in position and the end casting 27 therefor is bolted to the boss 67 by the bolts 70. The electric motor 11 may now be 40 secured to the offset 22 of the base casting 10, and the worm shaft 24 and worm 25 connected to the motor shaft and placed in mesh with the worm wheel 26, and the casting 28 bolted down by the bolts 29 upon the casting 27. It will be understood that the base casting 45 10 has been assembled with the tubing 15 and reservoir 14 therein, and as soon as the compressor head block 57 has been bolted down by screws 71, the pipes may be connected between the head block 57 and the coil 15, and between the tank 14 and the external system, as well as the return pipe 60 therefrom. Lastly, the fan 12 may be set up.

55 It will be noted that the unit is very compact and yet accessible. The valves permit the shutting off of the liquid refrigerant delivery and the withdrawal of substantially all gas from the external piping system, so 60 that upon the dismounting of the apparatus, the inlet valve in pipe 60 may be closed and thereafter the piping removed without substantial loss of obnoxious gases. Likewise, by closing the inlet valve in pipe 60 and there- 65 after the valve 62, the compressor may be

taken apart without appreciable escape of gases.

The liquefied refrigerant is delivered through a pipe 64 from the reservoir 14 to an expansion valve represented diagrammatically at 150 in Fig. 1. Thence the liquid refrigerant flows through a pipe 151 to an expansion tank 152, and makes its return through the pipe 60 to the compressor.

The construction of the expansion tank 152 is set forth in Fig. 7 as having a casing with the end walls 153 and 154, and a number of flues 155 therein, which are headed into the end walls to form gas-tight joints 160. A spiral baffle 156 causes the expanded gas to travel in a circuitous path over and around the several flues 155 until it arrives at the bottom of the expansion tank. The bottom of the expansion tank is shaped to drain toward a depression 157 which has communication with the return pipe 60 for the gaseous refrigerant. It will be observed that any oil carried along into the pipe 64 and 151 will flow down the walls of the flues and the baffle plates and is collected in the depression 157 and thence drained back to the compressor through pipe 60.

It is preferred to form the baffle plates of a series of distorted disks as represented at 156^a and 156^b in Fig. 7, which are joined at their abutting radial edges by the seams 156^c. It will be understood that the fit of the baffle plates around the respective flues need not be exact, since their purpose is merely to cause the expanded gas to move in a circuitous path instead of passing directly from inlet to outlet. The liquid entering through the pipe 151 is diverted into the discharge pipe 158 and permitted to discharge through apertures 159 thereof.

The bottom of the expansion tank receives and supports a sleeve 161 which is formed at its bottom edge with the projecting lugs 162 which are welded to the catch basin 163. This catch basin is formed as a funnel and at its downward apex terminates in a conduit 164 which supports a receiving cup 165.

Within the sleeve 161 are arranged the pent-roof plates 166 with the inwardly turned edges 167, and the downwardly extending brackets 168, which act as guides for the drawers, and prevent deposited moisture from dripping into them. In the front face of the sleeve 161 are provided apertures for the trays 169 with face plates 169^a. These are intended as customary for receiving water which is to be frozen into ice by the refrigerant, and which are supported in position by the screen 170 which in turn is supported at its periphery upon the sleeve 161.

Air cooled by the flues 155 flows downwardly and through the holes 171 in the plates 166 and between these plates; and makes its exit from the casing 161 through holes 172 and between the lugs 162, thus serv-

130

ing in its coolest condition to chill the water in the trays 169.

The method of operation of this expansion tank in the system is as follows: The tank for an ordinary ice box is about 12 inches in diameter and 18 inches long for the expansion chamber proper. The diameter of the flues 155 is represented as being around 2 inches. It is obvious that it is a very large area for this tank as compared with the presently employed tanks, so that there is a very large radiating surface for the treatment of the air confined in the refrigerator. The thermo-circulation of the air downwardly in the expansion tank compartment and upwardly in the food compartment of the refrigerator causes a rapid exchange of heat to occur. It will be noted that the thermostat which controls the operation of the electric motor is located at the upper part of the food compartment and therefore is exposed to the maximum temperature prevailing in the refrigerator.

The current of air flowing downwardly in the expansion tank compartment flows over and through the tank and is chilled thereby. The air flowing through the flues is diverted at the bottom by the baffle plates 166, and passes downwardly through the apertures 30 and through the space between the two plates 166. This air then flows over and around the drawers 169 containing water, and through the screen upon which the drawers rest, and finally makes an exit from the casing 161 through the several apertures provided. It is therefore to be seen that the temperature of the air is reduced by the expansion tank and that the cold air is caused to act upon the trays and thus to freeze the water within them.

During this movement downward of the air over and through the expansion tank, it separates a portion of its moisture onto the surface of the tank, and during the operating period of the refrigerating system proper, the cold expanded gas maintains the surface of the expansion tank slightly below freezing, to obtain an increased radiation therefor or absorption therefrom of heat by this gas. During this part of the operation the separated moisture tends to freeze and accumulate on the walls of the tank. Since the area of the tank is large, only a small quantity of water will be separated out on any particular portion thereof. When the refrigerating plant has reduced the internal temperature of the ice box to the required degree and has been shut down by the action of the thermostat, and the liquid refrigerant has been totally discharged by the balancing of the respective pressures, the walls of the tank are slightly warmed by the current of air, since they are no longer maintained cold by the internal gas. The walls remain substantially at the freezing point for a consid-

erable time owing to the latent heat required for melting the frost. After the frost melts, the water formed runs down over the outside of the expansion tank and down the inner walls of the flues, and is collected by the drip pan 163, inside and outside of the walls of the casing 161, and finds its way down the upper surface of this drip pan between the lugs 162. This water collects in the detachable cup 165, and since it is substantially at the freezing point, it serves as a heat storage unit for maintaining the temperature within the ice box, and by reason of the small surface of the cup, does not readily give off its moisture to the air.

Since the usual temperatures to be maintained within an ice box are between freezing and 40°, and a preferable temperature is 33 or 34°, it is obvious that by the use of the large surface of the present expansion tank, and by working the tank at the relatively high temperature range of 32 to 33°, that it is possible to maintain the surface of the tank substantially free from congealed moisture, which is well known to have a high heat insulating effect. In fact, it is found that by working the tank within these temperature limits, with alternate freezing and thawing of deposited moisture, that a tank having very slightly greater cooling surface than a usual super-cooled coil system is sufficient for an ordinary ice box.

The peculiar construction of the assembly renders the device suitable also for ventilating the room in which it is placed, or with which it may be connected by air conduits in other ways than that shown in Fig. 1. In Fig. 10, the apparatus is shown as disposed in a room having the side walls 101', 102' and the ceiling 103', with a shelf or floor 100' therein. It will be understood that the room may be of any size determined by architectural considerations, but that parts have been broken away for greater clearness in the drawings. The apparatus is mounted upon the floor or shelf 100' in this room, and is connected at one end by a conduit 104' with the air outside the room, and by a conduit 105' with the air adjacent the ceiling of the room, as well as by an opening at 106' with the air adjacent the machine itself. At the other end of the apparatus, it is connected by a pipe 107' with the air outside the room, and by a pipe 108' with the room adjacent the floor, or with a lower apartment: a pipe 109' likewise leads to a point near the ceiling of the room itself.

Each of the three communications is controlled by a double damper valve as shown in Fig. 11. While this valve has been illustrated for the connection of the pipes 107', 108', 109', it will be understood that a similar structure is used at the other end. Each of these damper devices comprises a casing with a pair of pivots 110', 111', having at the end outside of the casing a rigidly connected 130

operating handle 112', 113', respectively. Each of these handles has an offset lug 114' which is adapted to be snapped by the resiliency of the handle into one of the apertures 115' of the respective segment plate 116', so that the damper is held in a predetermined position. Rigidly connected to each of the respective shafts 110', 111' and within the casing is a damper 117', 118', which may be moved into and held by the means described above in any of three positions (horizontal, inclined, and vertical), corresponding to the three notches 115' on each of the sector plates. If the damper 117' is in the horizontal position shown in Fig. 11, all movements of air through conduit 109' is substantially shut off. If the damper 118' is then in the horizontal position, the sole movement of air through the casing occurs through pipe 107'. If the damper 118' be swung to the vertical position, all movement of air occurs through conduit 108'. If the damper 118' be in the horizontal position and damper 117', in the vertical position, all movement of air occurs through conduit 109'.

The inclined positions of the dampers are employed to give proportionate movements of air through two or more of the pipes. For example, when the damper 118' is in the inclined position shown in dotted lines in Fig. 11, and the damper 117' is closed, the movement of air occurs through both conduits 107' and 108'.

It is apparent that a similar construction as used at the other end of the apparatus will permit a similar regulation of the direction and movement of the air.

By such means, it is possible to move the air within the room, or to exchange the air either inwardly or outwardly through the ventilating system of the apparatus. Since an apparatus of this type may move, for example, 200 to 225 cubic feet of air per minute during its normal operation, it is apparent that the air in a kitchen of say 10 feet cube would be exchanged every five minutes. For example, in summer, the dampers may be set so that the hot air near the ceiling of the room is sucked through conduit 105' into and through the machine and delivered to the exterior of the building through conduit 107'. In winter, the cold air near the floor of the room may be drawn in through the opening 106', passed through the machine for cooling the coils and thereby itself be heated, and again delivered to the room near the ceiling through the pipe 109', or near the floor through the pipe 108'.

If the passage of fresh air through the room is desired or the removal of foul air required, the fresh air may be drawn in through pipe 104', and discharged into the room near the ceiling or floor, or the foul air from near the ceiling or floor may be discharged through the pipe 107'.

The base is a rigid structure containing the cooling coil for the hot refrigerant gases, over which a current of cooling fluid is caused to pass, and upon which are mounted the compressor and its driving mechanism.

It is obvious that changes may be made in the sizes and arrangements of the various parts without departing from the invention as set forth in the appended claims.

What I claim is:

1. In a mechanical refrigerating plant, a hollow base, a condensing coil in said base, a source of power rigidly mounted on said base, a compressor mounted rigidly on said base, power transmission means for connecting said source and said compressor, a ventilating fan and conduit rigidly mounted on and communicating with said base to force a current of fresh cool air over said condensing coil without passing over said compressor, and a pipe connecting the compressor discharge with said condensing coil.

2. In a mechanical refrigerating plant, a hollow base forming an air conduit, a condensing coil and a tank for condensed refrigerant located in said base, an electric motor mounted rigidly on said base, a ventilating fan mounted on said base and driven by said motor to force an air current through said base, a compressor mounted on said base and connected to said motor, and baffle plates in said base to cause such air current to move in a circuitous path over and around said coil and said tank, the intake end of said fan being removed in position and oppositely directed from the discharge end of said conduit in said base whereby fresh cool air is delivered by said fan to said conduit without passing over said compressor, and is discharged therefrom in a direction away from said intake end.

3. In a mechanical refrigerating plant, a chambered base, a compressor rigidly mounted on the outside of said base, a source of power rigidly mounted on the outside of said base, driving connection between said source of power and said compressor, a condensing coil for refrigerant gas connected to the discharge from said compressor and located in said chambered base, means operated by said source of power to deliver cooling fluid to said base at one point thereof and to withdraw it therefrom at a distant point without having passed over said compressor, and baffles in said base to cause the fluid to pass over and around said condensing coil.

4. In a refrigerating plant, a compressor for the expanded refrigerant gas, a source of power operatively connected to said compressor to drive the same, an air cooled condenser for the refrigerant gas to receive the same from said compressor, and means including a fan and conduits whereby fresh cool air may be drawn from the surrounding atmosphere

at a point remote from said compressor and source and delivered over said condenser without passing said compressor and source, said means including a conduit surrounding 5 said condenser whereby to prevent contact of said air with said compressor and to discharge the air after being heated by contact with said condenser at a point adjacent said compressor.

10 5. In a refrigerating plant for employment in an apartment, a compressor, an air conduit, a refrigerant condenser in said conduit, means to drive said compressor, means to cause air to move through said conduit, pipes leading from near the ceiling of said chamber respectively to the inlet and outlet ends of said conduit, pipes leading from the exterior of said apartment respectively to the inlet and outlet ends of said conduit, pipes leading 15 from the lower part of said apartment respectively to the inlet and outlet ends of said conduit, and dampers to selectively regulate the flow from and into said pipes into and from said conduit.

20 6. In a refrigerating plant for employment in an apartment, a compressor, an air conduit, a refrigerant condenser in said conduit, means to drive said compressor, means to cause air to move through said conduit, and 25 means including pipes communicating with the inlet and outlet ends of said conduit for selectively moving air to and from the exterior and predetermined interior points of said apartment, and dampers to selectively regulate the flow from and into said pipes into and from said conduit.

30 7. In a refrigerating apparatus, walls for providing a heat-insulated storage chamber, means to cool said storage chamber including 35 a mechanical refrigerating plant having a motor, a compressor and an air cooled condenser, a casing connected to said storage chamber walls, and a partition dividing the interior of the casing into compartments, said 40 motor, compressor and condenser being disposed in one of said compartments, a thermostat in said storage chamber, air conduits to said compartments, a fan to move air through said conduits and compartments and over said condenser, an electrical connection box and conductors therefrom to said thermostat and a source of power, and a separable connection between said box and said motor, whereby said motor, compressor and condenser 45 may be removed from said casing as an assembly.

50 8. In a refrigerating apparatus, walls for providing a heat-insulated storage chamber, means to cool said storage chamber including 55 a mechanical refrigerating plant having a motor, a compressor and an air cooled condenser, a closed casing connected to said storage chamber walls, said motor, compressor and condenser being mounted as a unit, an 60 apertured partition mounted on said unit

and dividing said casing into two compartments when positioned therein, said unit being positioned in one compartment, a fan to move air through said aperture and directed over said condenser, air conduits to convey air to and from said compartments, and means whereby said unit, partition and fan may be withdrawn as a whole from said casing.

65 9. In a portable refrigerating apparatus for use in an apartment, and including walls for providing a heat-insulated storage chamber connected with a closed casing, means to cool the said storage chamber including a mechanical refrigerating plant having an air cooled condenser, said plant and condenser being mounted in said casing, air conduits carried by said storage chamber walls and casing to take air from and deliver it to different points in said apartment, and a fan to move air through said conduits and over said condenser and thence over said motor and compressor.

70 10. In a gas expansion tank for refrigerating systems, a closed casing having side, top and bottom walls, open-end flues sealed at their ends into said top and bottom walls, a spiral baffle plate in said casing and around said flues, a conduit to deliver liquid refrigerant to said casing, a conduit to remove gaseous refrigerant therefrom, and means to collect liquid condensed on the walls of said casing and flues.

75 11. In a gas expansion tank for refrigerating systems, a closed casing having side, top and bottom walls, open-end flues sealed at their ends into said top and bottom walls, a spiral baffle plate in said casing and around said flues, a conduit to deliver liquid refrigerant into said casing, a perforated release 80 pipe in communication with said delivery conduit to discharge the liquid into the passage formed by said baffle plate, and a conduit to remove gaseous refrigerant from said casing.

85 12. In a gas expansion tank for refrigerating systems, a closed casing, a spiral baffle plate in said casing composed of a plurality of radially slit disks distorted out of plane, interlocking seams formed on the radial edges of said disks, and means to bring liquid refrigerant to and remove gaseous refrigerant from said casing.

90 13. In a gas expansion tank for refrigerating systems, a closed casing having side, top and bottom walls, a spiral baffle plate presenting a continuous gravitational surface, a sump formed in said bottom wall, a conduit to deliver liquid refrigerant to said casing adjacent said top wall whereby the same may expand and gasify during its downward movement along said baffle plate and admixed oil may trickle by gravity into said sump, and a conduit to remove the gaseous refrigerant from said casing.

14. In a gas expansion tank for refrigerating systems, a closed casing having side, top and bottom walls, a spiral baffle plate presenting a continuous gravitational surface, 5 a sump formed in said bottom wall, a conduit to deliver liquid refrigerant to said casing adjacent said top wall whereby the same may expand and gasify during its downward movement along said baffle plate and admixed oil may trickle by gravity into said sump, a conduit to remove the gaseous refrigerant from said casing, and a gravity conduit in communication with said sump to remove the gaseous refrigerant and oil therefrom. 15
15. In a gas expansion tank for refrigerating systems, a closed casing having air flues therein opening through the bottom wall of said casing, means to admit refrigerant medium to and withdraw it from said casing, jacket walls for providing a chamber mounted at the bottom of said casing having perforations therein, water trays supported in said chamber, and deflecting plates to cause 20 the cold air from said flues to traverse a circuitous path around said trays and through said perforations.
16. In a gas expansion tank for refrigerating systems, a closed casing and means to cool the same by expanding refrigerant medium, a sleeve at the bottom of said casing having downwardly projecting lugs to define air passages for the movement of air past the cool surfaces of said casing, and a 30 drip pan secured to said lugs and extending beyond said casing to receive the drip therefrom.
17. In a gas expansion tank for refrigerating systems, a closed casing having side, top and bottom walls, flues having open ends and sealed into said top and bottom walls, a sleeve secured at the bottom of said casing, a drip pan secured to the bottom of said sleeve with drainage apertures therebetween, and a receiving cup on said pan, whereby deposited moisture on said casing and flues may drain by gravity into and be collected by said cup. 40
18. In a gas expansion tank for refrigerating system, a closed casing having side, top and bottom walls, flues having open ends and sealed into said top and bottom walls, a sleeve secured at the bottom of said casing, a drip pan secured to the bottom of said sleeve with drainage apertures therebetween, water trays supported in said sleeve, angularly disposed roof plates over said trays to deflect dripping moisture therefrom, and a receiving cup on the said pan, whereby deposited moisture on said casing and flues may drain by gravity into and be collected by said cup. 50
19. In a gas expansion tank for refrigerating systems, a closed casing having side, top and bottom walls, flues having open ends and sealed into said top and bottom walls, a sleeve secured at the bottom of said casing, a drip pan secured to the bottom of said sleeve with drainage apertures therebetween, a horizontal perforated screen secured in said sleeve, water trays on said screen, baffle plates to deflect moisture from said trays and cause the cold air from said flues to traverse a circuitous path around said trays to the said apertures, and a receiving cup on the said pan, whereby deposited moisture on said casing and flues may drain by gravity into and be collected by said cup. 60
20. In a gas expansion tank for refrigerating systems, a closed casing having side, top and bottom walls, flues having open ends and sealed into said top and bottom walls, a sleeve secured at the bottom of said casing, and having apertures therein, a drip pan secured to the bottom of said sleeve with drainage apertures therebetween, a horizontal perforated screen secured in said sleeve, water trays on said screen, baffle plates to deflect moisture from said trays and cause the cold air from said flues to traverse a circuitous path around said trays to the said apertures, downwardly projecting members on said baffle plates to guide said trays and prevent passage of moisture from said plates into said trays, and a receiving cup on the said pan whereby deposited moisture on said casing and flues may drain by gravity into and be collected by said cup. 70
21. In a refrigerating plant, a compressor for the expanded refrigerant gas, a source of power to drive said compressor, a hollow base member, said compressor and source of power being rigidly mounted on said base, an air cooled condenser located in said base and communicating with said compressor to receive the compressed refrigerant gas therefrom, and a fan operated by said source of power and rigidly fastened on said base to force fresh, cool air through said base over said condenser and to discharge the air after being heated by contact with said condenser at a point remote from the intake, whereby said air is brought directly to said condenser without having passed over said compressor. 80
22. In a refrigerating apparatus, walls for providing a heat-insulated storage chamber, means to cool said storage chamber including a mechanical refrigerating plant having a motor, a compressor and an air cooled condenser, means providing a compartment in which said motor, compressor and condenser are located, a wall surrounding said condenser and providing an air conduit, a fan to move air from the exterior of said compartment through said conduit and over said condenser and thence into the part of said compartment external to said conduit, and a driving connection between said motor and said fan, whereby said fan is operated to 90

draw fresh cool air from the exterior of the compartment and pass it firstly over said condenser and thereafter over said compressor, said means being provided with an air outlet.

23. In a refrigerating apparatus, walls for providing a heat-insulated chamber, a compressor for the expanded refrigerant gas, means to drive said compressor, a casing disposed below and in alignment with said chamber, said compressor and driving means being located in said casing, a first vertical air conduit having an open top end, branch air conduits and a second vertical air conduit having an open bottom end, valve means to connect said first vertical air conduit to either of said branch conduits and the second air conduit to the other branch conduit, a device to actuate said valve means for reversing the connection, an apertured partition in said casing, said branch conduits communicating with the chambers at respective sides of said partition, an air-cooled condenser in said casing in communication with said compressor, and a fan mounted in the aperture of said casing.

24. In a refrigerator apparatus for use in an apartment, walls for providing a heat-insulated storage chamber, means to cool said storage chamber including a mechanical refrigerating plant having a motor, a compressor and an air-cooled condenser, a casing connected to said storage chamber walls, an air inlet conduit from said apartment opening into said casing, an air discharge conduit from said casing to a point outside the apartment in which said casing is located, said motor, compressor and condenser being located in said casing, and a fan for moving air through said inlet conduits and over said condenser to cool the same and thereafter through the discharge conduit to discharge the air outside the apartment, whereby leaking gases are discharged outside the apartment.

25. In a refrigerating apparatus, walls for providing a heat-insulated storage chamber, means to cool said storage chamber including a mechanical refrigerating plant having a motor, a compressor and an air-cooled condenser, a closed casing connected to said storage chamber walls, said motor, compressor and condenser being mounted as a unit, an apertured partition dividing said casing into two compartments, said unit being positioned in one compartment, a fan to move air through said aperture and direct it over said condenser, air conduits to convey air to and from said compartments, and means whereby said unit and fan may be withdrawn as a whole from said casing.

26. In a refrigerating apparatus, walls for providing a heat-insulated storage chamber, a casing connected to said storage chamber walls, a motor, a compressor and an air-

cooled condenser located in said casing, a conduit to admit air into said casing adjacent said condenser, a fan for moving air through said casing whereby the fresh air first encounters said condenser without passing over said motor and compressor, a conduit for discharging air from said casing, and means in said casing to prevent the flow of air from said motor and compressor over said condenser.

In testimony whereof, I affix my signature.
LUCIEN L. TORREY.
